EDWARD E. HINRICHSEN, OF NEW YORK, N. Y., ASSIGNOR TO WESTERN ELECTRIC COMPANY, INCORPORATED, OF NEW YORK, N. Y., A CORPORATION OF NEW YORK.

TELEPHONE SYSTEM.

1,254,691.

Specification of Letters Patent. Patented Jan. 29, 1918.

Application filed April 24, 1917. Serial No. 164,223.

To all whom it may concern:

Be it known that I, EDWARD E. HINRICHSEN, a citizen of the United States, residing at New York, in the county of New York and State of New York, have invented certain new and useful Improvements in Telephone Systems, of which the following is a full, clear, concise, and exact description.

This invention relates to telephone systems, and more particularly to such systems of the central energy type, its object being to reduce the amount of apparatus required in such systems.

In accordance with a feature of this invention, each telephone line is provided with one relay which controls both the line signal individual to the line and a supervisory signal associated with a connected link circuit.

This invention is illustrated in the accompanying drawings, wherein Figure 1 shows a telephone system containing one embodiment of the invention; and Fig. 2 is a perspective of the relay associated with the telephone line.

In Fig. 1 of the drawings there are shown two telephone lines—A and B—which extend from the subscribers' stations to a central office, and there terminate in jacks. A cord circuit C is also located at the central office for interconnecting the telephone lines.

Associated with each line is a relay 5 having two windings. This relay has two armatures—6 and 7—which are so adjusted that when the relay 5 is partially energized, upon the removal of the receiver from the switchhook, the relay attracts its armature 7 but does not attract its armature 6. Upon the attraction of this armature 7, while armature 6 is in its unattracted position, a line lamp 8 is lighted over a circuit which includes a normally open contact 27 (now closed) controlled by armature 7 and a normally closed contact 26 controlled by armature 6.

The lighting of the line lamp 8 is a signal to the operator that the subscriber has initiated a call which may now be answered

by the insertion of the answering plug 9 into line jack 10. Another circuit including the right-hand winding of relay 5 is now completed from battery through retardation coil 11, ring contacts of the answering plug 9 and the line jack 10, over one side of the line A, through the station apparatus, back over the other side of the line, and through the right-hand winding of relay 5 to ground. As a result of the establishment of this circuit, relay 5 is further energized to attract its armature 6, thereby opening the operating circuit of the lamp 8 which is thereupon effaced.

Should the subscriber on line A now restore the receiver to the switchhook, the hereinbefore referred to circuits of the line relay 5 would be opened, whereupon the relay would be deenergized and release both of its armatures. Upon the release of armature 6 an operating circuit for answering supervisory lamp 12 is established from battery through the lamp 12, sleeve contacts 70 of the answering plug 9 and the line jack 10, the contact 26 controlled by armature 6, and resistance 13 to ground. Answering supervisory lamp 12 is thereupon lighted to furnish a disconnect signal.

If, while the receiver at station B is on the switchhook, calling plug 15 be inserted into line jack 16, calling supervisory lamp 17 will be lighted over a circuit from battery through the lamp 17, sleeve contacts 80 of the calling plug 15 and line jack 16, and contact 26 controlled by armature 6 of the line relay 5—B, and resistance 13 to ground. Subscriber B may be signaled by the actuation of a ringing key 18, and the subscriber, 85 in response to the operation of the usual call bell, by removing the receiver from the switchhook, causes such an energization of line relay 5, that both of its armatures 6 and 7 are attracted, whereupon the circuit of lamp 17 is interrupted and the lamp is effaced. Line lamp 8—B, however, is not lighted, for contact 26 controlled by armature 6 is now open. When subscriber B re-

stores the receiver to the switchhook, relay 5 releases both of its armatures, again lighting calling supervisory lamp 17 to furnish a disconnect signal. The calling end of the 5 cord circuit is equipped with a retardation coil 21, similar to retardation coil 11, associated with the answering end.

In Fig. 2 the general construction of the line relay 5 is shown, which, it will be observed, is similar to the relay disclosed in the Craft Patent No. 1,156,671. The relay in this figure, however, has two armatures which are mounted upon opposite sides of the windings and upon a rearward extension 30 of the core. Both armatures are L-shaped, the short arms thereof being positioned upon opposite sides of a polar extension 31 of the core and in operative relation thereto. Armature 7 controls two contact springs 27, 27 supported by the rearward extension 30 and normally out of engagement. These contact springs 27, 27 are brought into engagement upon the attraction of armature 7 when the relay is either partially or 25 fully energized. Armature 6 controls two normally engaged contact springs 26, 26 which are forced out of engagement by the attraction of this armature upon the complete or full energization of the relay. 30 These contact springs are also mounted upon the rearward extension 30.

What is claimed is:

1. A telephone system comprising a telephone line extending from a subscriber's station to a central office, an electromagnet connected with the line, an armature for the electromagnet attracted upon partial energization thereof following removal of the receiver from the switchhook, a line signal 35 actuated upon attraction of the armature, a link circuit for extending the telephone line, another armature for the electromagnet attracted upon the further energization thereof resulting from the connection of the link 40 circuit with the line to restore the line signal, and a signal in the link circuit actuated by the deenergization of the electromagnet upon the subsequent restoration of the receiver to the switchhook while the link 45 circuit and the telephone line are connected.

2. A telephone system comprising a telephone line terminating at a central office, a line relay connected in the line and having two armatures, a link circuit for extending 55 the telephone line, a line signal controlled by the line relay actuated when one armature is attracted by the partial energization of the relay resulting from the closure of the line circuit and effaced when the other armature is attracted by the complete energization 60 of the relay resulting from the connection of the link circuit with the telephone line, and a supervisory signal in the link

circuit actuated upon the release of the second mentioned armature resulting from the 65 opening of the line circuit.

3. A telephone system comprising a telephone line terminating at a central office, a line relay having two armatures partially energized over the line upon the closure of 70 the line circuit to attract one armature, a line signal actuated upon attraction of the one armature, a link circuit for extending the telephone line, the connection of the link circuit with the telephone line causing 75 the further energization of the relay over the line to attract the other armature, thereby effacing the line signal, and a supervisory signal in the link circuit actuated by the deenergization of the line relay upon the opening 80 of the line circuit.

4. A telephone system comprising a telephone line terminating at a central office, a line relay having two armatures and partially energized over the line circuit upon 85 the closure thereof to attract one armature, a line signal, an operating circuit therefor completed upon attraction of the one armature and including contacts controlled by each armature, a link circuit for extending 90 the telephone line, the connection of the link circuit with the telephone line causing the further energization of the relay to attract the other armature to thereby interrupt the operating circuit, a supervisory signal in the 95 link circuit, and an operating circuit therefor completed upon the release of the second-mentioned armature resulting from the opening of the line circuit.

5. A telephone system comprising a telephone line terminating at a central office, a line relay having two armatures and partially energized over the line circuit upon the closure thereof to attract one armature, a line lamp, an operating circuit therefor 100 completed upon attraction of the one armature and including a normally closed contact controlled by the other armature, a link circuit for extending the telephone line, the connection of the link circuit with the telephone line causing the further energization of the line relay over the line circuit to attract the other armature and interrupt the operating 105 circuit, a supervisory lamp in the link circuit, and an operating circuit therefor completed, and including a contact of the line relay closed, upon the deenergization of the line relay by the opening of the line circuit.

6. A telephone system comprising a telephone line terminating in a jack, a line relay having two armatures and partially energized over the line upon the closure thereof to attract one armature, a line lamp, an operating circuit therefor completed upon attraction of the one armature and including a 115 normally closed contact controlled by the

other armature, a cord circuit terminating in a plug for extending the line circuit, the engagement of the plug and jack establishing a path over which the line relay is further energized to attract the other armature and interrupt the operating circuit, a supervisory lamp in the cord circuit, and an operating circuit therefor completed by the

deenergization of the line relay upon the opening of the line circuit and including the normally closed contact of the line relay and contacts of the engaged plug and jack.

In witness whereof, I hereunto subscribe my name this 20th day of April, A. D. 1917.

EDWARD E. HINRICHSEN.
